UNITED STATES PATENT OFFICE

140,236

DESIGN FOR AN OIL BURNER CASING

George W. Walker, Pleasant Ridge, Mich.

Application March 23, 1944, Serial No. 113,020

Term of patent 14 years

(Cl. D81—2)

To all whom it may concern:

Be it known that I, George W. Walker, a citizen of the United States, residing at Pleasant Ridge, in the county of Oakland and State of Michigan, have invented a new, original, and ornamental Design for an Oil Burner Casing, of which the following is a specification, reference being had to the accompanying drawings, forming a part thereof.

casing, as seen from the front, showing my new design.

I claim:

The ornamental design for an oil burner casing, substantially as shown.

GEORGE W. WALKER.
